UNITED STATES PATENT OFFICE.

JOHN M. PETERSON AND ALVIN O. RETRUM, OF DAWSON, MINNESOTA.

STORAGE-BATTERY PLATE AND METHOD OF BUILDING.

1,295,365.

Specification of Letters Patent. Patented Feb. 25, 1919.

Application filed December 11, 1917. Serial No. 206,659.

To all whom it may concern:

Be it known that we, JOHN M. PETERSON and ALVIN O. RETRUM, citizens of the United States, residing at Dawson, in the county of Lac qui Parle, State of Minnesota, have invented certain new and useful Improvements in Storage-Battery Plates and Methods of Building; and we do hereby declare the following to be a full, clear, and exact description of the invention, such as will enable others skilled in the art to which it appertains to make and use the same:

This invention relates to storage battery plates and the method of producing the physical structure of the same.

The invention has particular reference to the type of plate including a base from which radiate thin leaves in spaced relation to receive between them the active material. As is well known, it is highly desirable that the plate be formed in sections and that the leaves be spaced continuously of their lengths and be void of local condensations.

It is the object of the present invention to provide a method of producing the physical structure of the plate and to provide such a resultant plate as will insure these desirable attributes.

In the drawings:—

Fig. 1 is an elevation of a plate embodying the present invention and divided into regular sections, a portion being broken away.

Fig. 2 is a longitudinal section on line 2—2 of Fig. 1, and showing the radiating arrangement of the leaves, a portion being broken away.

Fig. 3 is a perspective view showing portion of the plate after formation of the scores.

Fig. 4 is a perspective view showing a portion of the plate and illustrating the manner in which the leaves tear during the cutting operation, portions of the first row of leaves being removed.

Fig. 5 is a plan view of a part of what is shown in Fig. 4.

Fig. 6 is an end view of a portion of the plate showing a portion of the first line of leaves as they are being formed.

Fig. 7 is an end view of a portion of a modified plate in which channels are formed instead of the plate being scored.

Fig. 8 is a view similar to Fig. 5 after the leaves have been formed.

Referring to the drawings and more par-

ticularly to Figs. 1 to 5 inclusive, in the practice of the present invention a flat sheet of lead 10 of proper dimensions is provided on both of its major faces with a plurality of scores 11, which scores are of such slight depth as to not produce any appreciable condensation of the metal at the sides of the scores and while the scores in the several views are shown as being formed equidistant and parallel, they may have any desired arrangement either direct or meandering so long as they may be crossed in the next step of the process.

The next step of the process is performed with a cutting tool illustrated at 12 in Fig. 4 of the drawings, which tool is drawn across a scored face of the plate while inclined laterally with respect to the face so as to form and turn up the leaves 13. In this cutting of the plate to form the leaves, the tool 12 is entered into the plate to a considerable depth equaling the entire depths of the resultant leaves and it is found that as the tool 12 progresses across the plate, it serves to rip each leaf during the formation of the leaf clear to the bottom of the cut made by the tool. This is illustrated in Fig. 4 of the drawings where on the under side of the plate 10 and the in-cut upper side of the plate the scores 11 are shown of slight depth while at 11' these scores are shown ripped to the bottom 13 of the cut indicated by dotted lines.

Thus, each leaf, during its formation, is torn at intervals corresponding to the positions of the scores and thus whether the scores are regular or irregular or straight or curved or whatever may be their arrangement or shape, this tearing occurs and the result is a leaf section of substantially uniform density and the leaves being thus of uniform density the electrolytic action in the subsequent utilization of the plate does not result in uneven swelling of the leaves and consequent buckling of the plate. Furthermore, the plate when charged presents uniform surfaces with a consequent even electro-chemical action, a uniform internal resistance throughout the superficial areas of the plate, with a battery of high efficiency.

In Fig. 6 of the drawings, there is illustrated a plate 15 in which channels 16 have been formed by bodily removal of metal to the full depth of the subsequent leaf while in Fig. 7 is illustrated the same section after

the leaves have been formed by cutting with a tool in the same manner as described in connection with Fig. 4, it being noted that the ends of the sections of the leaves 17 5 overhang the channels 16 in the direction in which the cutting tool progressed.

What is claimed is:

1. The method of forming a storage battery plate which consists in cutting the plate 10 with a resultant radiating leaf and tearing the leaf in the direction of the plate into sections.
2. The method of forming a storage battery plate which consists in cutting the plate 15 with a resultant radiating leaf and simultaneously tearing the leaf in the direction of the plate into sections.

3. The method of forming a storage battery plate which consists in scoring the plate and subsequently cutting the plate for a portion of its depth across the score in a manner to produce a radiating leaf and tear the latter from the bottom of the score to the base of the leaf. 20

In testimony whereof, we affix our signatures in the presence of two witnesses. 25
